(57) **CLAIM**

The ornamental design for a high pressure fuel injection pipe, as shown and described.

DESCRIPTION

FIG. 1 is a front view of a high pressure fuel injection pipe showing our new design;

FIG. 2 is a top view thereof;

FIG. 3 is a right side view thereof;

FIG. 4 is a left side view thereof;

FIG. 5 is an enlarged view along line 5-5 of FIG. 1;

FIG. 6 is a cross-sectional view along line 6-6 of FIG. 2;

FIG. 7 is an enlarged view along line 7-7 of FIG. 6;

FIG. 8 is an enlarged view of FIG. 4; and,

FIG. 9 is the enlarged view of FIG. 7 shown in a position of use.

The dashed broken line showing is included for the purpose of illustrating portions of the article that form no part of the claim. The dash-dot-dash broken line shown in FIGS. 1, 2, and 6 depict the boundaries of the claim and form no part thereof.

1 Claim, 5 Drawing Sheets(56)
